DISK POLISHING MACHINE

Charles C. Cratsenberg, Moline, Ill., assignor to
Deere & Company, Moline, Ill., a corporation
of Illinois

Application April 2, 1948, Serial No. 18,581

9 Claims.

(Cl. 51—97)

1

The present invention relates generally to grinding and polishing machines and is more particularly concerned with a new and improved machine for grinding the disks of plows, cultivators, disk harrows and the like, more particularly the concave faces thereof.

The object and general nature of the present invention is the provision of a disk grinding or polishing machine having a grinding or polishing wheel arranged for rotation about a generally fixed axis and means for supporting the disk to be ground or polished and shifting the same toward the grinding wheel and also relatively to the grinding wheel about an axis which is coincident with respect to the center of curvature of the disk surface being ground or polished.

Another feature of the present invention is the provision of a grinding or polishing machine which includes a swinging pendulum-type carrier supporting the work to be ground as well as the driving and work advancing and retracting means, all operating in conjunction with a grinding wheel mounted on the frame or base of the machine for rotation about a substantially fixed axis.

These and other objects and advantages of the present invention will be apparent to those skilled in the art after a consideration of the following detailed description, taken in conjunction with the accompanying drawings in which one preferred form of the invention has been shown by way of illustration.

In the drawings:

Figure 1 is a side view, with certain parts shown in section for purposes of clarity, of a disk grinding or polishing machine in which the principles of the present invention have been incorporated;

Figure 2 is a front view of the machine shown in Figure 1, showing particularly the swinging carrier which supports a work piece and the work piece advancing and retarding means and also the work revolving means;

Figure 3 is an enlarged sectional view of the connection between the lower end of the spline shaft carrying the disk to be polished and the pressure plate supporting the shaft; and

Figure 4 is a diagrammatic showing of the hydraulic system.

Referring now particularly to Figures 1 and 2, reference numeral 1 indicates the base or main support which includes a pair of side plates 2 connected together by transverse front and back plates 4 and 5, the plates being rigidly connected together, as by welding or the like. The side plates 2 are also interconnected by means of a bottom plate 6, a top housing plate 7, which are also welded to the front and back plates 4 and 5, and a pair of vertically spaced angularly disposed support plates 8 and 9. The upper plate 8 constitutes a support for a tubular quill member 10 in which a grinding wheel shaft 11 is

2

mounted by suitable bearing means or the like. The other angularly disposed support plate 9 is adapted to receive a motor 13 that is connected to drive the polishing wheel shaft 11 through belts 14 which are trained over pulleys 15 and 16 fixed to the grinding wheel shaft 11 and the shaft of the driving motor 13. The forward end of the shaft 11 carries a grinding wheel 18, and the support plates 8 and 9 are reenforced by suitable brackets or braces 21, 22, 23 and 24. Also welded to the forward edges of the upper portions of the two side plates 2 is a carriage-raising mechanism support plate 27 disposed at an angle to the vertical and substantially perpendicular to the axis of the grinding wheel shaft 11. The front plate 27, which forms the support for the carriage-raising mechanism described below, is formed with a central recessed portion 28, as best shown in Figure 2, for receiving the grinding wheel spindle shaft 11 and the forward portion 10 of the tubular quill member 10 therefor.

The mechanism for supporting the disk to be ground or polished includes a disk-receiving pendulum-like carriage unit, indicated in its entirety by the reference numeral 35. The unit 35 comprises a generally U-shaped yoke casting 36 having vertically disposed arm sections 37 and 38, which are interiorly threaded to receive the lower threaded ends of a pair of support rods 41 and 42, best shown in Figure 2. A lower extension 45 of the yoke 36 forms a support for a motor 46 which is connected, as described below, to drive the disk being polished. A central section 51 of the yoke 36 is formed as a shelf and is so constructed and arranged as to receive an upper casting 52, the upper portion of which is extended, as at 53, to form a bearing for a vertically disposed spline shaft 54, the splined portion 55 of which is shiftable generally vertically in a worm gear 56 that is journaled for rotation by bearing means 57 and 58 within the housing 59 that is formed by the central section 51 of the yoke and the cooperating upper casting member 52. These members are also formed to receive a worm shaft 61 which carries a worm pinion (not shown) which drives the worm gear 56. The outer end of the worm shaft 61 carries pulley means 63 (Figure 1) which is driven by belts 64 from a pulley means 65 that is fixed to the outer end of the shaft 66 of the motor 46.

The upper end of the spline shaft 55 carries a disk-receiving chuck or fixture 70, and the lower end of the shaft 55 is threaded to receive a pair of lock washers 74, the shaft 55 below the lock washers 74 being reduced in diameter, as indicated at 75, and carrying a spring 76 which bears at its upper end against the lock washers 74 and at its lower end against thrust bearing means 77 disposed in a recess in the central portion of a pressure plate 79. As best shown in Figure 3, the lower reduced end portion 75 of the spline shaft 55 is further reduced and threaded, as in-

dicated at 81, providing means for receiving a lower adjusting nut 82, adapted to be locked in different positions of adjustment by a cotter 83 or the like, and a washer 84 adapted to bear against the lower side of the pressure plate 79 to limit the upward movement of the spline shaft 55 relative thereto under the influence of the spring 76. The laterally outer end portions of the pressure plate 79 are apertured, as at 87, to receive the lower ends of a pair of piston rods 88 which form parts of a pair of ram units 89 which are mounted by any suitable means on the lower depending portion 92 of the yoke member 36. The ram units 89 are per se of conventional construction involving a piston and a cylinder, together with associated hose lines whereby fluid under pressure may be controllably directed into and out of the ram units 89 for exerting a pressure on the plate 79 to raise or lower the spindle shaft 55 and the disk-receiving chuck carried at the upper end thereof. When raising the chuck the pressure is exerted through the spring 76. The lower end of the spring 76 bears against a thrust washer 94 which forms a part of the thrust bearing means 77 mentioned above, said bearing means also including a washer 95. Between the washers 94 and 95 are ball bearings or the like, and the lower thrust washer 95 is disposed in a central recessed portion formed in the pressure plate 79. As best shown in Figure 3, this construction provides for rotation of the spindle shaft 55 relative to the pressure plate 79 and the yoke casting 36 while under the pressure exerted on the shaft by the spring 76.

The mechanism for raising and lowering the carriage 35 will now be described. The upper end of each of the rods 41 and 42 is received in a sleeve member 101, and each of the sleeve members 101 is provided with a laterally outwardly extending tapped boss 102 in which a stud 103 is fixed. The outer end of each of the studs is rockably disposed in the forward portion of a lug 105 which forms a forwardly projecting part of a vertically shiftable slide 106. Each of the two vertically shiftable slides 106 is mounted for vertical shiftable movement along ways 107 which are bolted or otherwise fixed to a mounting plate 108 that is bolted, as at 109, to the support plate 27. The upper ends of the rods 41 and 42 are supported for movement within the vertical bores 112 of the sleeve members 101, and the upper threaded ends of the rods 41 and 42 receive worm wheels 113 which mesh with worms 114 fixed to a transverse shaft 115 which is journaled in extensions 116 on the upper ends of the sleeves 101. Each end of the shaft 115 is squared to receive a crank or the like whereby the shaft may be turned, as desired, to rotate the worm wheels 116 and thus raise or lower the carriage 35 relative to the pivots 103 by which it is swingably mounted on the base 1.

The two pivot brackets 105 may be raised and lowered along the ways 107 on the mounting plate 108, so as to readjust the parts to compensate for wear of the grinding wheel and consequent reduction in diameter thereof, by means which will now be described. The supporting member 108 carries a forwardly extending apertured lug 125 at each upper corner portion thereof, and an interiorly threaded lug or projection 126 is carried on each bracket 106. A screw threaded shaft 128 is extended downwardly through each of the apertured projections 126, and at its upper end each of the shafts 128 extends upwardly through the associated lug 125. At its upper end each of the shafts 128 carries a worm wheel 131 securely

fixed thereto and acting through suitable bearing means 132 against the upper face of the associated lug 125. The latter members are provided with extensions 133 which form supports for a rotatable shaft 134 on the end portions of which worms 135, meshing with the associated worm gears 131, are mounted. The outer ends of the shaft 134 are squared to receive a crank or the like whereby the shaft 134 may be turned to rotate the two shafts 128 and thus raise or lower the support member 108 and the pivot-receiving brackets 106 thereon.

Referring again to the yoke or carriage unit 35, it will be seen from Figure 1 that each of the upper sections 37 and 38 of the yoke 36 is provided with a pair of inwardly extending lugs 141. A bail member 143 is pivotally connected to the lugs 141, as at 144 (Figure 1). As best shown in Figure 2, the bail member 143 preferably consists of two bail sections 145 and 146 spaced at their inner or adjacent ends to receive a pivot bolt 147, the sections 145 and 146 being rigidly connected together by a central section 148.

For swinging the carriage unit 35 relative to the grinding wheel 18, I provide a ram unit 150 disposed within the enclosure formed by the plates 4, 5 and 7. Preferably, the ram unit 150 is supported in any suitable way from the upper plate 7 and includes a piston rod 152 that extends forwardly through the front wall section 4 and pivotally connected through the bolt 147 with the link member or bail 143. A bracket 154 is fixed to the outer end of the piston rod 152, as best shown in Figure 1, and is fixedly connected to the outer end of a slide 155, preferably of I-beam cross section. The inner end of the slide 155 is supported within the housing formed by the plates 4, 5 and 7 by means of a support 156 that is fixed in any suitable way to the top plate 7 and/or to the ram unit 150, as desired. Switch-operating stops 158 and 159 are adjustably fixed to the slide 155, preferably within the aforesaid housing, and a similar switch-operating stop 161 is adjustably carried by the pressure plate 79, through lock nuts 163 or the like, and an apertured extension 164 on the lower portion of the lower depending portion 92, the extension 164 being apertured to receive the upper end of a rod 165 on which the stop 161 is adjustably mounted. Preferably, the lower portion of the rod 165 is screw threaded and the stop 161 fixed in position by a pair of lock nuts 166.

The operation of the disk polishing machine as so far described is substantially as follows:

Assuming that the carriage 35 and the supporting member 108 have been brought into the proper position relative to the base and the grinding or polishing wheel 18, the operator first starts the motors 13 and 46, which causes the polishing wheel 18 and the disk D on the fixture 70 to rotate, the operator also starting up the motor M of a hydraulic power unit which includes a pump driven by the motor, a reservoir, conduits to and from the ram units 89 and 150, and other appendages forming a part of the hydraulic system that controls the rams 89 and 150. The hydraulic system may be of any suitable construction and the particular details thereof do not per se form a part of the present invention. Having started the motors M, 13 and 46, the operator then actuates suitable valve means to direct fluid under pressure into the lower ends of the cylinders of the hydraulic units 89 to raise the spindle 55 and so cause the disk D to approach the rotating polishing wheel 18.

When the disk D has been raised to the proper position, depending upon how much pressure it is desired to exert through the spring 76 during the polishing operation, the stop 161 actuates a limit switch L¹ which acts through a suitable solenoid valve or the like to direct fluid under pressure into the forward end of the cylinder forming a part of the ram unit 150. This causes the piston rod 152 thereof to be moved inwardly (to the left as viewed in Figure 1), and this movement acts through the ball or link 143 to swing the carriage 35 inwardly relative to the grinding wheel 18 and causes the latter to polish the entire inner surface of the disk D. When the piston rod 152 has been moved through such an extent as to complete the polishing operation the stop 158 acts through a second limit switch L² to cause the spindle 55 to be lowered and at the same time to cause the piston rod 152 to be forced forwardly or outwardly (to the right as viewed in Figure 1) thereby swinging the carriage 35 forwardly or outwardly into the position shown in Figure 1. This movement continues until the stop 159 actuates a third limit switch L³ which terminates the outward movement of the piston rod 152 and shuts off the motor 46, thereby bringing the spline shaft 55 to a stop. The polished disk D is then removed and an unpolished disk inserted and the process repeated.

As mentioned above, the ram units 89 and 150, together with the limit switches L¹, L² and L³, may be incorporated in various hydraulic and electrical circuits, as desired, and I do not intend to limit my invention to any particular cycle and/or timing of operation. However, I have shown one form of hydraulic circuit in Figure 4 with which the disk polishing machine of the present invention may be equipped. Referring now to Figure 4, the reference numeral 200 indicates a source of fluid from which a pump 201 driven by the motor M withdraws fluid and delivers the same under pressure into a main conduit 202 and two high pressure branches 203 and 204. The branch 203 leads to a solenoid-hydraulic valve unit 205, and fluid may be delivered by the valve unit 205 back to the reservoir 200 through a conduit 206. The other high pressure branch 204 leads to a similar electro-hydraulic valve unit 208, and the latter unit may deliver fluid back to the reservoir 200 through a return line 209. The valve unit 205 includes a pair of solenoids 211 and 212 for operating the control valve, and the valve unit 208 similarly includes solenoids 213 and 214 for a like purpose.

The two ram units 89 are interconnected by leads 215 and 216, and the latter are connected by conduits 217 and 218 with the valve unit 205. The ram units 89 control the raising and lowering of the shifttable disk-carrying unit 35. The ram unit 150 that swings the carriage 35 toward and away from the polishing wheel 18 is connected with the valve unit 208 by conduits 221 and 222. Counterbalance valve units 226 and 227 are interposed in the lines 218 and 221, and a flow control valve 228 is interposed in the line 22. Return check valves 229 and 230 are interposed in the conduits 221 and 222 adjacent the valve unit 208, and another check valve 231 is associated with the high pressure branch line 204.

The electrical circuits interconnecting the motors M, 13 and 46, and the associated limit switches and solenoids are omitted from the diagrammatic showing in Figure 4, since such circuits do not per se form any part of the present invention.

In operation, when the solenoid 212 is energized fluid is caused to flow under pressure through the conduits 218 and 216 into the ram units 89 to raise the disk D into a grinding position, and when the disk reaches the proper position the limit switch L¹ is actuated which, through connections (not shown), energizes the solenoid 214 which causes fluid to flow under pressure past the valves 230 and 227 and through the line 221 to the ram unit 150 to cause the carriage 35 to be swung inwardly, whereby the rapidly rotating polishing wheel 18 grinds or polishes the concave surface of the disk D. When the stop 158 actuates the limit switch L² the latter acts, through circuits not shown, to deenergize the solenoids 212 and 214 and energizes the solenoids 211 and 213. These units shift the valves 205 and 208 so as to cause the ram units 89 and the ram unit 150 to cause the carriage 35 to lower and at the same time to be swung outwardly toward the position shown in Figure 1. Then when the carriage 35 is returned to the position just mentioned the stop 159 acts against the limit switch L³ to deenergize the solenoids 211 and 213, whereupon the disk spindle motor 46 is stopped and the other parts held in position to accommodate the removal of the ground and polished disk and the substitution therefor of the next disk to be ground or polished, whereupon the series of operations as described above is repeated.

While I have shown and described above the preferred structure in which the principles of the present invention have been incorporated, it is to be understood that my invention is not to be limited to the particular details shown and described above, but that, in fact, widely different means may be employed in the practice of the broader aspects of my invention.

What I claim, therefore, and desire to secure by Letters Patent is:

1. A machine for polishing the concave side of concavo-convex disks, comprising a support, a disk-carrying work holder including a yoke, a rotatable chuck carried by the yoke in a generally vertical position, a pair of upwardly extending arms connected at their lower ends with said yoke, means carried by said support for pivoting the upper ends of said arms for swinging movement relative to said support about an axis which contains the center of curvature of the concave side of a disk mounted on said yoke, a grinding wheel rotatably mounted on said support generally in a plane parallel to the axis of swinging of said yoke whereby the latter is movable toward and away from said grinding wheel, said yoke arms being spaced apart so as to move on opposite sides of said chuck and said grinding wheel, and means for raising and lowering said yoke arms relative to said support so as to adjust said yoke to correspond to different curvatures of each disk.

2. A machine for polishing the concave side of concavo-convex disks, comprising a support including a base section and a pair of laterally spaced apart members extending upwardly and forwardly from said base section, a disk-carrying work holder, a part swingably mounted on the upper and forward portions of said laterally spaced apart member, vertically adjustable means on said swingably mounted part for connecting said work holder thereto for movement toward and away from said base section about a generally transverse axis, a rotatable chuck mounted on said work holder and adapted to

receive a disk with the concave side thereof facing upwardly, with said disk disposed generally centrally between said laterally spaced apart members and with the central of curvature of said concave side lying in said transverse axis, means for rotating said chuck, a grinding wheel unit mounted on said base section generally between said laterally spaced apart members and including a grinding wheel and a motor for driving said wheel, peripheral portions of said grinding wheel engaging the concave face of said disk when said work holder is swung toward and away from said grinding wheel, means to operate said vertically adjustable means for raising and lowering said work holder relative to said grinding wheel so as to adjust the work holder so as to accommodate disks of different curvatures, and means for swinging said work holder.

3. A machine for polishing the concave side of concavo-convex disks, comprising a base having a lower portion and an upwardly and forwardly angled portion overhanging the lower portion, a disk carrier, means for swingably mounting said disk carrier on the overhanging portion of said base about a transverse axis and including means for supporting a disk with its concave side facing upwardly, and means for rotating said disk, a grinding wheel mounted for rotation on said base at an acute angle to the horizontal and in a position generally rearwardly of the vertical plane of said transverse axis, being adapted to engage the concave side of said disk when the carrier is swung upwardly and rearwardly toward said grinding wheel, and means carried by said base and connected with said disk carrier for swinging the latter toward and away from said grinding wheel.

4. A disk polishing machine comprising a base having an upper portion, a disk carrier comprising a yoke, a disk-receiving spindle mounted on said yoke for rotation about a generally vertical axis and for axial movement in a generally vertical direction in said yoke, means on said yoke for rotating said spindle, means on the yoke for raising and lowering the spindle relative to said yoke, means for swingably supporting said disk carrier on the upper portion of said base for movement about said transverse axis, a disk polishing tool carried by said base below said upper portion and rotatable about an axis extending in a downwardly and forwardly extending direction, said tool being disposed rearwardly of the vertical plane passing through said transverse axis, and means for shifting said disk carrier inwardly of said base toward said tool, said disk carrier normally being suspended below said transverse axis in a position generally in front of said tool when removing and replacing disks on said carrier.

5. A disk polishing machine comprising a base including a pair of upwardly extending side plates, said plates being disposed in spaced apart relation, a rotatable shaft carrying a disk polishing wheel at its forward end mounted on said base between said plates in such a position that the axis of said shaft extends downwardly and forwardly and the plane of rotation of said wheel extends upwardly and forwardly, a supporting plate disposed between said upwardly extending base plates and lying in a plane generally parallel to the plane of rotation of said polishing wheel, a member mounted for vertical adjustment along said last mentioned plate and carrying a pair of brackets extending generally forwardly there-

from, a carrier for disks to be polished, comprising a lower disk-receiving member and a pair of upwardly extending laterally spaced apart arms pivotally connected at their upper ends to said forwardly extending brackets, said arms being spaced apart a distance sufficient to clear said polishing wheel when swung toward the latter, and means on said base for swinging said disk carrier toward and away from said polishing wheel.

6. The invention set forth in claim 5, further characterized by means for raising and lowering said brackets relative to said supporting plate, and means for raising and lowering said disk carrier arms relative to their pivotal connection with said brackets.

7. A disk polishing machine comprising a base having an upwardly extending portion, a power driven polishing wheel carried by said base below said upwardly extending portion, a disk carrier comprising a disk-supporting member and a pair of laterally spaced apart arms fixed at their lower ends to said supporting member, means pivotally connecting the upper ends of said arms with the upper portion of said base, said arms being spaced so as to clear said polishing wheel and the disk supported on said carrier, said disk carrier including disk-receiving means, a vertical shaft rotatably mounted in said carrier, a drive wheel having a splined engagement with said shaft and held against axial movement in said carrier but accommodating, by virtue of said splined engagement, vertical movement of said shaft and the disk-receiving means at the upper end thereof, means on said disk carrier connected with the lower end of said shaft for raising said disk-receiving means on the disk thereon into operative engagement with said polishing wheel, and means for swinging said disk carrier toward said wheel when the disk-receiving means has been elevated to bring the disk thereon into engagement with said wheel.

8. The invention set forth in claim 7, further characterized by a part rotatably connected with the lower end of said disk carrier shaft, a spring acting between said part and said shaft for transmitting raising movement from said part to said shaft, and raising means on said disk carrier acting against said part for raising said shaft.

9. The invention set forth in claim 7, further characterized by a motor carried by said swingably disk carrier, a cross shaft carried by said carrier and having driving engagement with said splined gear, and means for driving said cross shaft from said motor.

CHARLES C. CRATSENBERG.
